(57) **CLAIM**

The ornamental design for a cat crawling frame, as shown and described.

DESCRIPTION

FIG. 1 is a perspective view of a cat crawling frame, showing my new design;

FIG. 2 is a front view thereof;

FIG. 3 is a back view thereof;

FIG. 4 is a top view thereof;

FIG. 5 is a bottom view thereof;

FIG. 6 is a left side view thereof; and,

FIG. 7 is a right side view thereof.

The broken lines illustrate portions of the cat crawling frame that form no part of the claimed design.
